(57) **CLAIM**

The ornamental design for a bolt, as shown and described.

DESCRIPTION

FIG. 1 is a front view of a bolt showing my new design, the rear view being a mirror image of the front view.

FIG. 2 is a top plan view of the bolt;

FIG. 3 is a bottom view of the bolt;

FIG. 4 is a right view of the bolt, the left view being a mirror image of the right view;

FIG. 5 is a sectional view taken along line 5-5 of FIG. 2 of the bolt; and,

FIG. 6 is a perspective view of the bolt.

The broken lines show portions of the article and form no part of the claimed design.

1 Claim, 6 Drawing Sheets
